(57) **CLAIM**

The ornamental design for a tripod, as shown and described.

DESCRIPTION

FIG. 1 is a front perspective view of the tripod showing my new design;

FIG. 2 is a back elevational view thereof;

FIG. 3 is a right side elevational view of the tripod;

FIG. 4 is a left side elevational view thereof;

FIG. 5 is a front elevational view of the tripod;

FIG. 6 is an enlarged front perspective view of an upper telescoping fitting on the fragmentary portion of the tripod shaft, the lower fitting and leg portions are omitted for ease of illustration;

FIG. 7 is an enlarged front perspective view of a lower telescoping fitting on the fragmentary tripod shaft portion and enlarged fragmentary legs, the upper fitting is omitted for easy of illustration;

FIG. 8 is an enlarged bottom perspective view of a brace fitting on the enlarged fragmentary tripod shaft and legs portion;

FIG. 9 is a top elevational view of the tripod; and,

FIG. 10 is a bottom elevational view thereof.
